US00D995415S

(12) **United States Design Patent** (10) **Patent No.:** **US D995,415 S**
Guo et al. (45) **Date of Patent:** **** Aug. 15, 2023**

(54) **PORTABLE POWER STATION**

(71) Applicant: **Shanghai Gotion New Energy Co., Ltd.**, Shanghai (CN)

(72) Inventors: **Haiyang Guo**, Shanghai (CN); **Xiansheng Yang**, Shanghai (CN); **Shengli Wang**, Shanghai (CN)

(**) Term: **15 Years**

(21) Appl. No.: **35/514,586**

(22) Filed: **May 13, 2022**

(80) **Hague Agreement Data**

Int. Filing Date: **May 13, 2022**

Int. Reg. No.: **DM/221525**

Int. Reg. Date: **May 13, 2022**

Int. Reg. Pub. Date: **Jul. 1, 2022**

(30) **Foreign Application Priority Data**
